UNITED STATES PATENT OFFICE.

JOHN ZELLWEGER, OF CHICAGO, ILLINOIS.

BOILER GAS-FURNACE.

SPECIFICATION forming part of Letters Patent No. 258,525, dated May 23, 1882.

Application filed January 12, 1882. (No model.)

To all whom it may concern:

Be it known that I, JOHN ZELLWEGER, a citizen of the United States, residing at Chicago, in the county of Cook and State of Illinois, have invented certain new and useful Improvements in Boiler Gas-Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to that class of boiler and other furnaces in which a gaseous fuel is used mixed with atmospheric air, the latter being heated prior to its admission into the burner or combustion-chamber by passing it through a chamber or flue which is heated by the out-going products of combustion.

The invention consists in the construction and combination of parts, which will hereinafter be more fully described, and then set forth in the claims.

In the accompanying drawings, Figure 1 is a vertical longitudinal section of a boiler gas-furnace embodying my improvements. Fig. 2 is a vertical transverse section taken through the lines *x x*, Fig. 1. Figs. 3 and 4 are similar sectional views taken respectively through the lines *y y* and *z z* of Fig. 1. Figs. 5 and 6 illustrate a modified construction of burner and air-inlet flues.

The letter A designates a horizontal flue, which serves for conducting a gaseous fuel from a suitable gas producer, holder, or reservoir into a vertical extension or chamber, *a*, located at the end of said horizontal flue. The roof of this chamber *a* is provided with a series of ports or openings, *b*, which permit the entrance of the gaseous fuel into the mixing or combustion chamber B, where it meets and mingles with atmospheric air discharged into said chamber B through the ports *d*, made in the rear thereof. The openings *d* are arranged exactly opposite the solid portion or bridges, between the openings *b* in the floor of the mixing-chamber, so as to bring the two series of openings out of line with each other for insuring a better diffusion or mixing of the gas and

air. The commingled gas and air are ignited in the chamber B, and the resultant flame passes through an opening or slot, *e*, in the top of the combustion-chamber, and strikes a deflector, C, which consists of a vertical front plate, a horizontal top plate, and a series of vertical partition-plates arranged over the slot or opening *e*, so as to form a series of distinct passages for the escape of the flame into the boiler-chamber P. The products of combustion pass under the boiler E to the rear of the chamber P, and thence through the flues of the boiler into a vertical flue, F, located in front of the boiler and combustion chamber. This flue F conducts the products of combustion into a horizontal bottom flue, D, which is arranged below the burner and leads into a recuperator or regenerator chamber, G, which extends in a rearward direction to the smoke-stack of the furnace. The recuperator G is divided into two longitudinal top and bottom chambers, *g g'*, by means of a metallic partition-plate, H, which extends the entire length of said recuperator, as is clearly shown in Fig. 1. The upper chamber, *g*, at its rear or stack end receives the necessary amount of atmospheric air for burning the gas in the combustion-chamber, and said air in passing forward becomes heated by contact with the iron plate or partition H, and rises into the combustion-chamber through the openings *b* to mingle or combine with the gas admitted therein. The metallic partition-plate H may either be smooth or it may be corrugated, for increasing the heating or radiating surface thereof, and in certain instances I propose to substitute inverted troughs, instead of said partition, for forming independent conducting-flues. I also propose to heat the air by passing it through a series of pipes extending through the top of the recuperator.

I have herein represented the recuperator as extending under the boiler, which is the preferable location thereof; but it will be obvious that it may be placed outside of the furnace between it and the stack. In all cases, however, it starts in the rear of the burner, just below where the air enters the combustion-chamber.

The gas-flue A is in the various figures of the drawings shown as running parallel with the flues D for the escape of the products of combustion; but I desire it to be understood

that instances may occur when it will be found necessary to locate the gas-flue at right angles to the boiler. In such a case the escape-flues D are arranged or made to pass below the gas-flues.

5 The burner or combustion-chamber itself may be arranged at right angles to the boiler, as is shown in Figs. 1 and 3; but I also propose to arrange it so as to run lengthwise with the boiler, as is illustrated in Figs. 5 and 6. In the latter instance the air heating and supply chamber is branched at its front end, so as to admit air into the combustion-chamber through a double series of inlet-openings, e.

15 The outlet of the combustion-chamber herein shown is made in the form of a contracted slot or fissure, so as to produce a short flame for preventing the condensation of carbon, as soot on the boiler, and obviating the production of

20 a smoky flame. The combustion-chamber is in communication with a firing-hole, M, which extends through the front of the furnace-wall, and is of special service for starting the fire when working the furnace intermittently, and for cleaning the

25 gas-ports. It is well known that coal-gas and cold air do not burn readily in a cold burner, and hence a small fire from shavings and kindling-wood

30 maintained in the firing-hole M for a short time will serve to properly warm the burner. The firing-hole may be provided with a grate, and it has a door for closing it during ordinary service. This door is generally provided with

35 a register for regulating the amount of air admitted through the firing-hole.

A curved shield, u, arranged at the front of the boiler, passes around a man-hole in the boiler-shell, as shown in Fig. 2.

In place of the partitioned deflector herein shown, I may use an arched deflector, which covers and projects over the flame-orifice of the burner. In order to reduce the loss of heat, it is of advantage to provide the door in front of the boiler-flues with a non-conducting cover, or to make it double with an intermediate air-space.

Having thus described my invention, what I claim as new, and desire to secure by Letters Patent, is—

1. In a gas-burning furnace, the combination of the vertical escape-flue F, the bottom flue connecting therewith, and the partitioned recuperator H, having upper air-heating chamber, g, and bottom chamber, g', for the outgoing products of combustion, and a burner located at the front end of the air-heating chamber, substantially as and for the purpose set forth.

2. In a gas-burning furnace, the combination of the horizontal firing-hole M and vertical escape F, surrounding the same, with the burner B, arranged at the rear of the firing-hole, as and for the purpose set forth.

3. In a gas-burning furnace, the combination of the burner B, having a contracted outlet, e, for the flame, gas-inlet openings b, and air-supply openings d, and the superposed deflector c, with gas-supply flue A, and hot-air flue g, as and for the purpose set forth.

In testimony whereof I affix my signature in presence of two witnesses.

JOHN ZELLWEGER.
